UNITED STATES PATENT OFFICE.

WILLARD STRAUB, OF LOS ANGELES, CALIFORNIA.

DESIGN FOR A JUICE-EXTRACTOR.

52,684.

Specification for Design.

Patented Nov. 12, 1918.

Application filed May 18, 1918. Serial No. 235,423. Term of patent 3½ years.

To all whom it may concern:

Be it known that I, WILLARD STRAUB, a citizen of the United States, residing at Los Angeles, in the county of Los Angeles and State of California, have invented a new, original, and ornamental Design for a Juice-Extractor, of which the following is a specification, reference being had to the accompanying drawing, forming part thereof, in which:

The figure is a perspective view of a juice extractor showing my new design.

I claim:

The ornamental design for a juice extractor as shown.

WILLARD STRAUB.
